CLAIM

The ornamental design for a hand exercise egg, as shown and described.

DESCRIPTION

FIG. 1 is a perspective view of a hand exercise egg. FIG. 2 is a top view of a hand exercise egg. FIG. 3 is a bottom view of a hand exercise egg. FIG. 4 is a front view of a hand exercise egg, which is identical to the back view; and, FIG. 5 is a right-side view of a hand exercise egg, which is identical to the left-side view. The broken lines depict portions of the hand exercise egg that form no part of the claimed design.
